UNITED STATES PATENT OFFICE.

JAMES WITHERINGTON, OF TRENTON, NEW JERSEY, ASSIGNOR TO THE TRENTON IRON COMPANY, OF SAME PLACE.

IMPLEMENT FOR STRETCHING WIRE.

SPECIFICATION forming part of Letters Patent No. 324,285, dated August 11, 1885.

Application filed January 21, 1885. (No model.)

To all whom it may concern:

Be it known that I, JAMES WITHERINGTON, a citizen of the United States, residing in Trenton, New Jersey, have invented an Improved 5 Implement for Stretching Wire, of which the following is a specification.

The object of my invention is to provide a device which can be readily employed to stretch sections or lengths of twisted or cabled 10 wires, whether barbed or plain, employed to form wire fences.

A preferred form of an implement conveniently embodying my invention is represented 15 in the accompanying drawings and described in this specification, the particular subject-matter claimed as novel being hereinafter definitely specified.

In the drawings, Figure 1 is a side elevation representing a practical mode of employing 20 my device. Fig. 2 is a top plan view of an implement embodying my invention. Fig. 3 is a central vertical section of the same, and Fig. 4 a side elevation of the same.

Similar letters of reference indicate corresponding parts in all the figures.

A is the stem, body, or core of the device, the same being a cylinder of metal, conveniently made hollow, and equipped at its lower extremity with a point, a. Near its lower extremity the stem is provided with a circumferential step or horizontally-extending flange, a'. Closely encircling the cylindric stem is a tubular sleeve, B, so accurately fitted as to be capable of rotation upon the said sleeve, resting or stepped upon the step a', and extending almost to the top of the stem. At its upper extremity the sleeve is provided with a ratchet-face or circular ratchet, b.

C C' are two hook-provided collars which 40 loosely encircle the sleeve, and which respectively rest upon a circumferential rib, a'', formed upon it and upon the step a'. The hooks of these collars are designated c c'. The upper hook-provided collar is extended laterally to 45 form a bearing, c'', for a stop-pawl, D, which is mounted upon the upper face of said bearing. The stop-pawl, in the mounting of the parts, is in range of engagement with the teeth of the ratchet-face b of the sleeve. A pawl-spring, d', applied to the bearing of the stop-

pawl, bears on said stop-pawl and retains it to duty when not forcibly deflected by its handle d.

Mounted so as to closely encircle the tubular sleeve, and resting upon the upper face of the ratchet or top of the tubular sleeve, is a ratchet-actuating lever, E, which is adapted to turn freely upon the tubular stem. This actuating-lever is provided with an actuating-pawl, e, which in the mounting of the parts is set to engage the teeth of the ratchet-face of the sleeve, and which is held to duty by a spring, e'. The actuating-lever is held in position upon the tubular sleeve by a lock-nut, F, on the stem. The tubular sleeve is also provided with a series of radially-projecting tie pins, hooks, or kindred devices, G.

Such being a description of the construction of my device, its operation is as follows: The implement as an entirety being pressed into the ground in a vertical position—in, for instance, propinquity to a post, as H, Fig. 1, a tree, or other fixture—chains or ropes I are made fast between said post and the hooks of the hook-collars. The cables or wires W which are to be stretched are then made fast either directly to the tie-pins of the tubular sleeve or else through the medium of disk-cam cable-splices or eccentric cam-grips S, of a character well known to wire-fence makers, to short sections W' of wire or ropes, themselves connected to the tie-pins of the sleeve. The ratchet-actuating lever is then deflected in the direction of the arrow in Fig. 2, with the result that its actuating-pawl, being in bite with the ratchet face of the tubular sleeve, occasions a predetermined rotation of said sleeve corresponding to the throw of said actuating-lever. After its throw the tubular sleeve is automatically locked by the stop-pawl. The actuating-lever is then thrown back, its actuating-pawl slipping over the teeth of the ratchet, and a further advance rotation is made by it, the result of which operation is that the tubular sleeve is rotated to the desired degree, and the cables, ropes, or wires attached to it wound up upon it as upon a winding-drum, with the further result of stretching the cables of the fence entirely taut. Of course it is essential to effect the engagement of the hook-collars

with a fixture, as otherwise there would be no point of rigid bearing for the stop-pawl or of resistance for the implement as an entirety.

Having thus described my invention, I claim 5 and desire to secure by Letters Patent—

1. In a wire-stretching implement, the combination of a central body, core, or stem, a sleeve mounted to rotate thereon, and provided with a ratchet-face and with pins or hooks, 10 hook-collars adapted to be connected with a fixed point of support and so to maintain the implement in a fixed position, a stop-pawl, and a ratchet-actuating lever provided with an actuating-pawl which engages with the ratchet-face of the tubular sleeve, substantially as described.

2. The combination, in a wire-stretching implement, of a body, core, or stem having a tapering or pointed lower extremity and pro-

vided with a shoulder or step, a tubular sleeve 20 mounted so as to rotate upon said core or body and resting upon said step, two hook-provided collars mounted upon said tubular sleeve, one of which is provided with a stop-pawl adapted to engage the ratchet-face formed upon the 25 sleeve, and a ratchet-actuating lever mounted upon the implement and provided with a spring-controlled actuating-pawl engaging with the ratchet of the tubular sleeve, substantially as set forth.

In testimony whereof I have hereunto signed my name this 2d day of January, A. D. 1885.

J. WITTINGTON.

In presence of—

HENRY D. SCUDDER,
W. C. STRAWBRIDGE,
J. BONSALL TAYLOR.
